UNITED STATES PATENT OFFICE.

CARL ERIC ANDERSON, OF PRINCE BAY, NEW YORK, ASSIGNOR TO THE S. S. WHITE DENTAL MANUFACTURING COMPANY, A CORPORATION OF PENNSYLVANIA.

DENTAL IMPRESSION-TRAY.

1,369,768.

Specification of Letters Patent.

Patented Mar. 1, 1921.

Application filed July 18, 1918. Serial No. 245,449.

To all whom it may concern:

Be it known that I, CARL ERIC ANDERSON, a subject of the King of Sweden, and a resident of Prince Bay, in the county of

5 Richmond, State of New York, have invented certain new and useful Improvements in Dental Impression-Trays, of which the following is a specification, reference being had to the accompanying drawings.

10 My invention relates particularly to that class of devices which are employed by dentists in taking the impressions of the human mouth, and is especially directed to the form and manufacture of such devices.

15 The principal objects of my invention are, to provide a dental impression tray that may be stamped from a single blank of sheet material, to produce a light, strong, efficient, inexpensive unitary structure.

20 Other objects of my invention are, to provide a dental impression tray so constructed and arranged as to afford ample rigidity yet permitting distortion sufficient to adapt it to the different conditions to be found in 25 the human mouth.

Specifically stated, the form of my invention as hereinafter described comprehends a dental impression tray having the upturned wall of its plaster-receiving bowl extended 30 to form a handle.

My invention also includes all of the various novel features of construction and arrangement as hereinafter more definitely described.

35 In the accompanying drawings, Figure 1 is a plan view of an impression tray constructed in accordance with my invention; Fig. 2 is a side elevational view of said impression tray; and Fig. 3 is a central vertical longitudinal sectional view taken on the line 3—3 in Fig. 1.

In said figures the plaster-receiving bowl 1 is of substantially semi-circular contour having its perimetral wall 2 upturned and 40 provided at its medial region with a projection extending downwardly and outwardly to form a handle in unitary relation with said bowl, by which the tray may be conveniently manipulated.

50 As best shown in Fig. 1, the downwardly extending portion 3 of the handle curves laterally in substantial conformity with the curve of the perimetral wall of the bowl 1, and the outwardly extending portion 5 of said handle is provided with the depression 6 forming a rib, and curving

transversely in a vertical plane, whereby ample rigidity of the structure is afforded while permitting sufficient distortion of the tray to accommodate it to different conditions to be found in practice.

It may be here noted that impression trays are adapted for use in taking impressions of either the upper or lower mandible, and when employed for the lower mandible will 65 obviously be inverted from the position illustrated, therefore, where the upturned wall and downwardly extending projecting portion is herein referred to, it is to be understood that reference is had to the structure as positioned in the drawings.

My invention is advantageous in that by so forming the impression tray, it may be stamped from a single blank of sheet material, preferably metal, thereby providing 75 a structure which is not cast and therefore not cumbersome, as are the trays in which the bowl and handle are separately formed and united by solder or rivets.

Although the handle of the tray is shown 80 in the drawings as extending from the forward edge of the bowl, it will be obvious that it may, if desired, be extended forwardly from the inner edge of the bowl, and therefore, I do not desire to limit my invention to the precise details of construction, as it is obvious that various modifications 85 may be made therein without departing from the essential features of my invention as defined in the appended claims.

Having thus described my invention, I claim:

1. A dental impression tray having the upturned wall of its plaster-receiving bowl 95 extended downwardly and outwardly to form a handle, and having a central longitudinally extending depression arranged to form a bracing rib in said handle.

2. A dental impression tray formed of 100 sheet material and having the upturned wall of its plaster-receiving bowl extended downwardly below the plane of the bottom of said bowl, and outwardly to form a handle, whereby a space is afforded between 105 the rear wall of said bowl and handle.

In witness whereof, I have hereunto set my hand this 8th day of July, A. D., 1918.

CARL ERIC ANDERSON.
